CLOTH FINISHING

Sanford L. Cluett, Troy, N. Y., assignor to Cluett,
Peabody & Co., Inc., Troy, N. Y., a corporation
of New York

Application March 3, 1933, Serial No. 659,485

2 Claims. (Cl. 26—57)

This invention relates to mechanism for shrinking cloth and more particularly to a tentering or like machine of the kind in which cloth is stretched in width while in a state of longitudinal relaxation, an example of such machine being that illustrated in United States Patent No. 1,734,897 and German Patent No. 556,392.

The prior machine of said patents includes a suitable elevated guide member adapted to cause the cloth to approach the traveling pins of the tenter at an angle with respect to their horizontal plane of travel, in combination with a novel form of impaling device in which the first or primary brush presses on the cloth at the initial point of contact of the cloth with the traveling pins. The cloth being impaled is part way down on one pin by the time it is engaged by the point of the next succeeding pin. Thus, the length of the cloth between two successive pins is represented by approximately the hypotenuse of a right triangle of which the base is the distance of between the two successive pin points. Upon passage under the primary impaling brush, the difference between the hypotenuse and the base of said right triangle then appears as lengthwise slack available to permit superficial lengthwise contraction of the impaled cloth as the consequence of widthwise stretching.

Thus a characteristic of the machine of said patents is that the cloth is initially impaled in a lengthwise uncreased or unwrinkled state while under longitudinal tension, and that a longitudinal slackness is later afforded by a subsequent shortening of the linear distance between points of engagement of the cloth with successive pins, more specifically by a shortening of such distance from the length of the hypotenuse to the length of the base of the same right triangle. Designating the angle between said hypotenuse and said base as α , the impaling angle, it will at once appear that the lengthwise slack finally attained will be a function of said angle and that the greater the impaling angle the greater the amount of lengthwise slack obtained. With a machine constructed as described above it is practicable for a given length of the tenter chain to have evenly distributed thereon from 0% to approximately 10% excess of cloth, depending on the value of the impaling angle α .

If the cloth is allowed to run freely to the pins which are constantly advancing it, the primary impaling brush is free to drop to a position where the impaling angle α attains its maximum value, permitting the pins to draw in to the tentering machine, for example, a 10% excess of cloth. On the other hand, holding back on the cloth approaching the pins raises the primary impaling brush, decreases the impaling angle α , and diminishes the amount of cloth drawn into the machine by the pins. For the purpose of holding back on

the cloth to an appropriate degree to provide the requisite level for the primary impaling brush, the requisite angle of impaling, and a predetermined degree of slackness after impaling, the machine of said patents includes a pair of rollers which serve to retard the rate of travel of the cloth to the impaling brush.

As will be understood from the foregoing, there is no slack in the cloth between these retarding rollers and the tenter pins, and indeed in practice the uniform impaling of the cloth necessitates the absence of any slack, and the existence of some degree of tension in this portion of the cloth. The present invention provides an arrangement of these retarding rollers such that in preparing a machine for starting, the operator can thread the cloth through these rollers and onto the pins without regard to the possible temporary creation of slack in the cloth, and can then merely rotate these retarding rollers backward to provide adequate tension in the cloth before beginning operation of the machine.

In the accompanying drawings:

Fig. 1 is a side elevation of the entering end of a cloth shrinking tentering machine according to this invention;

Fig. 2 is a vertical partial section on the line 2—2 of Fig. 1 with certain parts broken away;

Fig. 3 is a vertical section on the line 3—3 of Fig. 2;

Figs. 4 and 4^a are diagrammatic views, to a larger scale, showing the manner in which the tensioned cloth is impaled on the tenter pins and subsequently caused to lie slack thereon.

Referring to Fig. 1, the tentering machine, the frame of which is indicated at 11, includes the usual spaced and diverging runs of traveling web-edge holding devices such as the usual chain-driven tenter pins, of which one run is indicated at 12. As customary, the two runs of pin chains are preferably driven by suitable driving connections from a source of power such as an electric motor.

The web of cloth *w* which may have previously passed through any suitable device for straightening and smoothing it, enters the illustrated device by passing around rolls 70 and 71 and from thence runs at an inclination to the primary impaling brushes of which one is indicated at 80. The impaling brush 80 is freely rotatable, to turn with the passing cloth, and is supported in a floating manner by the cloth *w*, for example by having its axle mounted on a lever 82 pivotally mounted at 83 on a bracket 84 fixed to the frame of the machine. A spring 85 pulls on the lever 82 so as to press the brush firmly against the cloth which in turn is impaled on the pins. The spring 85 is preferably adjustable so that heavier pressure may be obtained for correspondingly heavier fabrics. A secondary impaling brush 86 rotating 120

freely on its axle is preferably provided to press the cloth firmly down near or to the base of the pins. The axle 87 of the brush 86 is fastened firmly to the bracket 84, but may be moved to or 5 from the pins so that the brush may push the cloth down to the proper distance. The cloth is drawn into the pins by the force resulting from the horizontal pull of the last pin on which the cloth is impaled, in conjunction with the radial 10 pressure of the brush 80.

Fig. 4 shows the primary impaling brush 80 in its lowest position, and illustrates how with this 15 position of the brush the cloth would be impaled by the pins at a large angle α with respect to the horizontal, with resulting large excess of cloth between adjacent pins.

Fig. 4a showing the impaling brush sustained by the tension in the cloth in a somewhat more elevated position, illustrates the resulting smaller 20 impaling angle α that is obtained by holding back or retarding the cloth w before the latter comes in contact with the pins. Obviously if the cloth w is held back under sufficient appropriate tension, the impaling brush 80 will be raised still 25 higher until its periphery is tangent to the horizontal plane of the points of the pins, at which time the angle α will be zero, the hypotenuse of the angle α will be equal to its base, and the cloth will therefore be impaled merely on the points of 30 the pins and drawn in to the pins at a rate exactly equal to the forward travel of the pins.

In order to hold back on the cloth, so as to obtain higher positions of the impaling brush than that shown in Fig. 4, and correspondingly smaller 35 impaling angles, the retarding rollers 70 and 71 are provided. However, instead of connecting these rollers to the tentering machine in the manner shown in said patents, the present invention provides connections which permit the rolls 40 70 and 71 to be turned backward when necessary or desirable. Thus the connections from the tentering machine to these rollers 70 and 71 prevent these rollers from turning as fast as the cloth would otherwise turn them, but do not prevent 45 these rollers from turning at a slower rate or from remaining stationary or from being turned backward, even though the tenter pins are in motion.

As shown in Figs. 2 and 3, each roller 70 and 50 71 is mounted to rotate freely on ball bearings 40 carried by cross-shafts 43 and 44. A pawl or series of pawls 45 and 46 provided on the end faces of the rolls 70 and 71 respectively are adapted to engage ratchet wheels 47 and 48 which 55 are keyed onto the respective cross-shafts 43 and 44. Any suitable light springs 45a and 46a may be employed to urge the pawls 45 and 46 toward their respective ratchet wheels. As shown in Fig. 3, the arrangement of the ratchets is such that 60 the roller 70 and 71 can not be turned by the cloth at a faster rate than is permitted by the cross-shafts 43 and 44 but can turn at a slower rate, (the ratchet wheels running freely ahead of the pawls), or can be turned backward.

65 The cross-shafts 43 and 44 are connected by any desirable gearing or through electric or other control to run in synchronism with the tenter chains, for example, by connections extending to the drive motor of the tenter. Preferably provision is made for varying the speed 70 ratio between the travel of the tenter pins and the rate of rotation of these shafts 43 and 44. In the illustrated form of the device, shafts 43 and

44 are connected by bevel gearing 49, 50, 51, 52 to a vertical shaft 53, which in turn is connected by gears 54, 55, shaft 56, and gears 57, 58 to a change speed gear device indicated at 59, preferably constructed and arranged as shown in the United States patent application of Sanford L. Cluett, Serial No. 628,852, filed August 15, 1932, and including a small longitudinally movable idler gear 73 adapted to be engaged with any one of a plurality of gears 74 of varying diameters. A handle 75 is adapted to hold the idler gear 73 in engagement with the appropriate larger gear 74 to provide the appropriate speed of the cross-shafts 43 and 44 relative to the travel of the tenter pins. The change speed gear device 59 is in turn connected by gears 78, 79, (Fig. 2) to a shaft 80 connected to the drive motor for the tenter. Thus the rotation of the two rolls 70 and 71 may be limited to any predetermined and desired rate of speed with respect to the tenter pins, and the tenter pins thereby prevented from drawing cloth onto the machine at any faster rate than that selected. A suitable scale 76 (Fig. 1) may be employed to indicate the amount of excess cloth which is permitted to be drawn into the machine.

The advantage of the ratchet and pawl connection between the rolls 70, 71 and the shafts 43, 44 will now be readily apparent. In preparing the machine for operation, the operator can initially start the machine, whereupon the tenter pins, gearing and cross-shafts 43, 44 will begin to move. The rolls 70, 71, however, will remain stationary as the ratchet wheels 47, 48 can move freely past the associated pawls. The operator 105 can then pass the cloth web w around and between the rolls 70, 71, which can be rotated manually at any desired speed not in excess of the speeds of shafts 43, 44. After drawing the cloth through these rolls, the operator can then stop 110 the machine, and impale a short length of the cloth on the pins by hand. Thereupon, to provide the desired tension in the cloth in advance of the impaling brush, the operator can turn the rolls 70, 71 backward the requisite amount. The 115 machine is then ready for continued operation.

I claim:

1. A tentering machine for cloth-shrinking having means for impaling the entering cloth on traveling tenter pins and subsequently causing 125 the points of impalement to lie closer together so as to provide lengthwise slack in the impaled cloth, and having cooperating rollers adapted to retard the entering unimpaled cloth so as to limit the amount of cloth drawn onto the machine by 130 impaling operation, characterized in that a ratchet device prevents the rollers from being turned by the cloth faster than a predetermined rate with relation to the travel of the tentering pins but permits the rollers to be turned backward to facilitate applying the proper tension to 135 the entering fabric.

2. A tentering machine comprising traveling web-edge holding devices, a moving part running in synchronism therewith, rotary cloth-retarding 140 means engaging the traveling cloth prior to engagement by said traveling web-edge holding devices, and a ratchet connection between said cloth-retarding means and said moving part limiting the speed of said rotary cloth-retarding means in a forward direction but permitting said rotary means to be turned backward.

SANFORD L. CLUETT.
